ELECTRIC ICE CRUSHER

Downer P. Dykes, Lawrence, Kans., assignor, by mesne assignments, to Rimco, Inc., Kansas City, Mo., a corporation of Missouri

Filed June 10, 1963, Ser. No. 75,287

Term of patent 14 years

(Cl. D89—1)

Fig. 1.

Fig. 2.

Fig. 3.

Fig. 4.

FIG. 1 is a front elevational view of an electric ice crusher embodying my design;

FIG. 2 is a side elevational view thereof, the opposite side view being substantially a mirror image;

FIG. 3 is a rear elevational view thereof; and

FIG. 4 is a top plan view thereof.

I claim:

The ornamental design for an electric ice crusher, as shown, and described.
